UNITED STATES PATENT OFFICE.

JOSEF PALLWEBER, OF FURTWANGEN, BADEN, ASSIGNOR TO SIGMUND STERN, OF FRANKFORT-ON-THE-MAIN, GERMANY.

WATCH-CASE SPRING.

SPECIFICATION forming part of Letters Patent No. 447,473, dated March 3, 1891.

Application filed May 27, 1890. Serial No. 353,303. (No model.)

To all whom it may concern:

Be it known that I, JOSEF PALLWEBER, a subject of the Emperor of Austria, residing at Furtwangen, Baden, Germany, have invented a new and Improved Self-Closing Watch-Case, of which the following is a specification.

My invention relates to an improvement in spring-lids for watches; and the object of my invention is to provide a spring-lid which, having been opened, as usual, by a pressure on the knob or crown, will automatically close again as soon as said pressure has been released.

15 In the accompanying drawings, Figure 1 is a central longitudinal section of the watch-case with the lid closed. Fig. 2 is a transverse section of the same seen from below. Fig. 3 is a transverse section of the same 20 seen from above, and Fig. 4 is a face view of the open watch-case. Fig. 5 is a detail side view of the operating mechanism, and Fig. 6 an end view thereof.

The letter A represents a shaft that is connected to a knob or crown B, by which it may be pressed down. The shaft A engages one 25 end of a steel-spring hoop D, placed within one half of the watch-case. The upper end of hoop D is hook-shaped, as at C, and engages the lid and keeps it closed; but when the shaft A is pressed down it carries the end of 30 hoop D with it, and the hook C releases the lid and allows it to open.

The opening and closing of the lid are effected as follows: The lower end of the spring-hoop D bears against one arm of a lever F, pivoted at E to the watch-case. When the 35 hoop D is forced down, the lever-arm in contact with said hoop will be also forced down and the opposite lever-arm will therefore be raised. Through this other lever-arm passes a pin G, which is secured to the lid. This 40 pin G is lifted by the lever-arm, and the lid is consequently revolved on its hinge and is 45 opened as soon as the knob or crown B is

pressed down. A spring H, arranged in that half of the watch-case opposite to the hoop D, acts with a constant pressure on the lever-arm opposite to the arm that is acted upon by the hoop D. The spring H serves to automatically close the lid as soon as the knob or crown B has been released.

The self-closing of the lid is effected by the pressure of the spring H on the lever F, which, being forced down again, carries with it the pin G, whereby the lid is closed. At the same time the other lever-arm lifts the hoop D and brings the hook C at the upper end of said hoop into engagement with the lid to lock the same. It will be seen that the lid is kept open 60 so long as the pressure continues on the knob or crown B, while when said pressure is taken off the lid closes automatically.

The lower end of hoop D may be connected to the lever F by means of a small pin engaging a hole or by other suitable means. The lower end of spring H may be connected to the other arm of lever F in the same manner. In this way a reliable working of the mechanism is obtained.

What I claim is—

1. The combination of a watch-case with a pair of springs D H, a lever F, acted upon by both of said springs, a pin G, carried by said lever, and a lid engaged by said pin, substantially as specified.

2. The combination, in a watch-case, of a spring D, having hook C, with stem A, that engages said spring, and with spring H, lever F, engaged by springs D H, pin G on lever 80 F, and a lid engaged by said pin, substantially as specified.

In testimony whereof I hereunto sign my name, in the presence of two subscribing witnesses, this 28th day of April, 1890.

JOSEF PALLWEBER.
